ATTORNEY

UNITED STATES PATENT OFFICE.

DAVID S. SHORT, OF INDIANAPOLIS, INDIANA.

SPARK-PLUG.

1,335,762.

Specification of Letters Patent.

Patented Apr. 6, 1920.

Application filed November 26, 1917. Serial No. 204,023.

To all whom it may concern:

Be it known that I, DAVID S. SHORT, a citizen of the United States, residing at Indianapolis, in the county of Marion and State of Indiana, have invented certain new and useful Improvements in Spark-Plugs, of which the following is a specification.

This invention is a spark plug more particularly adapted for use in firing the explosive charges of an internal combustion engine, wherein suitable terminals are formed for the passage of a spark across a gap, and within the body of the insulator an adjustable and secondary spark gap is provided.

15 One object of the invention is to provide a spark plug having the usual insulated terminal that is connected to one section of the insulated electrode, and provided for adjustment with and to the usual section of the 20 electrode.

Another object of the invention is to provide a spark plug having an insulator formed in parts, the lower one of which is adapted to coöperate with the lower section 25 of the electrode and be adjustably held said section being provided at one end with rounded or tapered points to form spark points.

A further object of the invention is to 30 provide a spark plug with an electrode formed of section, each one of which is adjustable relative to the other, and one of the sections is further adjustable relative to the spark point carried by a shell.

35 Broadly stated, the invention comprises a spark plug having a threaded metallic shell adapted to receive a sub-divided insulator having a longitudinal bore, the lower portion of the insulator being provided with a flange and a petticoat, said flange being adapted for engagement with a shoulder formed in the shell, the other portion of the insulator being substantially cylindrical and provided at one end with 40 a flange, and a recess therein concentric to the bore, the opposite end of said portion of the insulator being provided with threaded engaging means, a sub-divided electrode disposed within the insulator, one section 45 of which is disposed within one portion of the insulator, each section of said electrode being provided with screw threads to cooperate with suitable nuts for providing separate adjustment relative to each other 50 within the insulator, one of said nuts being disposed within the concentric recess, means

for holding and retaining said insulator and electrode to coöperate with one end of one of the sections of said electrode, and a terminal connected with the other section of 60 said electrode, said electrode being provided with suitable sparking points within the insulator that are adapted to form a secondary spark gap.

One practical form of construction and 65 assembly will be described and illustrated in the accompanying drawings, in which:—

Figure 1 is an elevation of the assembled spark plug,

Fig. 2 is a vertical sectional view of the 70 plug shown in Fig. 1, and

Fig. 3 is a sectional view on the line 3—3 of Fig. 2.

In the preferred embodiment about to be described the spark plug is provided with 75 the usual hexagonal metallic threaded shell 5 that is provided internally with a bore 6 having a shouldered portion 7 where the bore is of greater diameter and forming threads within these larger diametered portions of the bore. The threads 9 are formed adjacent one end so that the plug may be screwed into the walls of an internal combustion engine.

At the lower end of the shell 5 there is 85 provided the usual stationary electrode 10 that may be L-shaped as shown. The free end of the electrode 10 is adapted to form a spark point. To coöperate with the threads 8 the threaded locking nut 11 is employed. This nut may be also hexagonal so that it may be engaged by a wrench when so desired. The shell 5 may be also engaged with a wrench for screwing into and out of the walls of the engine.

95 Disposed within the shell 5 there is an insulator, which in the present illustration is shown as being formed in two parts indicated at 12 and 13. The portion 12 is provided with a longitudinal bore 14 and adjacent its upper end it is provided with threaded means 15. The lower end of this portion is formed to provide a flange 16 and within the flange and concentric to the bore 14 there is provided a recess 17. This 100 recess is adapted to receive a nut 18, one face of which lies flush with the end of the insulator 12.

The other portion 13 of the insulator is 110 also provided with a flat upper surface to engage with the flat under surface with the upper portion 12. The portion 13 is pro-

vided with a body portion having a rounded flange 19 that is adapted to be seated on the rounded shoulder 7. The portion 13 is also provided with a downwardly projecting 5 petticoat 20. The petticoat is provided with a longitudinal bore 21 of larger diameter than the longitudinal bore 22 passing through the body portion. To coöperate with the nut 18 there is a section 23 that 10 forms one portion or section of the electrode.

As shown the section 23 is provided with the tapered ends 24 and 25. The upper portion of the section 23 is provided with threads 26 that are adapted to coöperate 15 with the nut 27 and with the nut 18. The nut 27 is positioned at the bottom of the bore 21 and upon the opposite side of the body portion of the insulator portion 13 to that on which the nut 18 is disposed.

20 The coöperation between the nuts 18 and 27 will permit the section 23 to be moved vertically with respect to the fixed electrode and with the section 28 of the electrode. The section 28 of the electrode is prefer- 25 ably threaded as indicated at 29 through- out the greater portion of its length. It is further provided with a tapered point 30 that is adapted to coöperate with the tapered point 25. The threads 29 are tapered to co- 30 operate with the threaded means 15. The insulator portion 12 has in engagement at one end a lock washer 31 that also coöperates with the threaded section of the electrode 28.

Coöperating with the washer 31 there is 35 a thumb nut 32 that also runs on the threaded electrode 28. The upper end of the electrode 28 may be slotted as indicated at 33 so that a suitable tool may be engaged to rotate the section and thus screw it in and 40 out. It will be seen from the several points of construction that the sections 23 and 28 may be adjusted relative to each other and with respect to the stationary electrode 10. The points 25 and 30 may also serve as a 45 secondary spark gap.

What I claim is:

1. A spark plug, comprising a metallic

shell having a shoulder formed interiorly thereof, a sectional insulator core, the lower section of which is provided at the top with 50 an exterior flange adapted to be seated on the interior shoulder of the shell, the upper section of said core having a flange at its lower edge adapted to rest upon the flange portion of said lower section, the bore ex- 55 tends through the sectional insulator, the lower end being of an enlarged diameter and a sectional electrode adjustably mounted within said bore, one section of said electrode positioned to depend within the bore 60 of the upper insulator section, the other electrode section adjustably disposed within the enlarged bore of the lower insulator section and adjusting means within the larger bore for projecting the lower electrode par- 65 tially into the bore of the upper insulator section, to create a secondary spark gap with respect to the other electrode section and within the bore of the upper insulator.

2. A spark plug comprising a metallic 70 shell having a shoulder formed interiorly thereof, a sectional insulator core, the lower section having its top flange adapted to be seated upon the interior shoulder of the shell, the other section having a flange at 75 its lower edge adapted to rest upon the flange of the lower section, the bore extending through the sectional insulator core, a sectional electrode adjustably mounted in said bore and threaded adjusting means car- 80 ried by said upper insulator section for engag- 85 ing and projecting the electrode there- in, adjusting means provided in the lower insulator section for gripping an electrode section supported therein, said means grip- ping and supporting said electrode section within the bore of said insulator.

In testimony whereof I affix my signature in presence of two witnesses.

DAVID S. SHORT.
